LADY'S STOCKING

William G. Bley, Paisley Road, Richboro, Pa., assignor of one-half to Richard M. Spurgeon, Philadelphia, Pa.

Filed Apr. 15, 1960, Ser. No. 60211

Term of patent 14 years

(Cl. D47—7)

FIG. 2

FIG. 1 is a side view of a stocking, with a portion thereof folded upon itself, embodying my invention; and
FIG. 2 is a fragmentary view thereof showing in detail the heel portion of the design as seen from the rear.

I claim:

The ornamental design for a lady's stocking, as shown.
